US0D1028878S

(12) **United States Design Patent** (10) **Patent No.:** **US D1,028,878 S**
(45) **Date of Patent:** **** May 28, 2024**

(54) **INFORMATION HANDLING SYSTEM CHARGER**

(71) Applicant: **Dell Products L.P.**, Round Rock, TX (US)

(72) Inventors: **Mark J. Law**, Singapore (SG); **Benedict Tiong Chee Tay**, Singapore (SG)

(73) Assignee: **Dell Products L.P.**, Round Rock, TX (US)

(**) Term: **15 Years**

(21) Appl. No.: **29/829,645**

(22) Filed: **Mar. 7, 2022**

Related U.S. Application Data

(63) Continuation of application No. 29/819,007, filed on Dec. 13, 2021.

(57) **CLAIM**

We claim the ornamental design for an information handling system charger, as shown and described.

DESCRIPTION

FIG. 1 is a front perspective view of the information handling system charger;

FIG. 2 is a front elevation view of the information handling system charger;

FIG. 3 is a rear elevation view of the information handling system charger;

FIG. 4 is a right side view of the information handling system charger;

FIG. 5 is a left side view of the information handling system charger;

FIG. 6 is a top view of the information handling system charger;

FIG. 7 is a bottom view of the information handling system charger; and,

FIG. 8 is a rear perspective view of the information handling system charger.

Broken lines shown in the drawings illustrate portions of the information handling system charger and form no part of the claimed design.

1 Claim, 6 Drawing Sheets
